UNITED STATES PATENT OFFICE.

LEONID MANDELSTAM, OF BERLIN, AND HERMANN BRANDES, OF STRASSBURG, GERMANY.

WIRELESS SIGNALING SYSTEM.

SPECIFICATION forming part of Letters Patent No. 776,337, dated November 29, 1904.

Application filed September 8, 1904. Serial No. 223,748. (No model.)

To all whom it may concern:

Be it known that we, LEONID MANDELSTAM, doctor of philosophy, a subject of the Emperor of Russia, residing at No. 35 Joachimsthalerstrasse, Berlin, Germany, and HERMANN BRANDES, a subject of the King of Prussia, Emperor of Germany, residing at Strassburg, (Physikalisches Institut der Universität,) Alsace, Germany, have invented certain new and useful Improvements in Wireless Signaling Systems, of which the following is a full, clear, and exact description, reference being had to the accompanying drawings, forming a part of this specification.

This invention relates to a wireless signaling system in which there is employed as transmitter a simple transmitter, or a so-called "coupled" transmitter—that is to say, an aerial conductor in conductive or inductive connection with an exciting-circuit—and also as receiver an aerial conductor in conjunction with a receiving-circuit containing a detector.

This invention is intended to obtain in such telegraph systems as close a tuning as possible of the receiver to the transmitter. For this object it has been found necessary that the receiver-circuit should be loosely coupled with the aerial conductor and also that the damping of the receiving-circuit be reduced as far as possible and the capacity of the receiving-circuit kept as far as possible constant.

Where in the present invention a simple transmitter is employed, of course no mention of a coupling is necessary; but in all cases where by the present invention the operation is carried out with a transmitter which consists of an aerial conductor and an exciting-circuit connected therewith it is assumed that the coupling of these two circuits is a firm one, as has also hitherto been customary.

Wien (*Wied. Ann.*, B. 8, 1902,) has theoretically examined the combination of various coupled transmitters and receivers. The result of this examination tends to show that a loosely-coupled receiver affords advantages only in combination with a loosely-coupled

transmitter, and, further, that this combination while admitting a close tuning between 50 the transmitting and receiving stations must in principle have a much smaller scope than the combination of a firmly-coupled transmitter with an also firmly-coupled receiver. By the loose coupling of two vibrating systems Wien understands a coupling in which the back action is so small that the coupled system in case of resonance of the two separate systems only shows vibrations of a single vibration period (this is similar to the self-vibration of each separate system) in contrast to a firm coupling in which the coupled system shows two vibrations, one of which is smaller and the other larger than the self-vibration of the uncoupled systems. The researches of Wien are of a purely theoretical character and take for granted data which are also theoretically deduced.

In the specification of the present invention the theory stated by Wien is taken as 70 characteristic of the loose coupling. Now experiments have shown that the combination of a firm coupled or a simple transmitter with a loosely-coupled receiver not only allows of 75 close tuning, but also the bridging over of wide distances, assuming that the secondary system of the receiver is formed so as to be adapted to be closely tuned by suitable dimensioning of the constituents and by a suitable method of switching. In all the vibration-circuits coming in question in the transmitter and receiver the secondary circuit of the receiver (the detector-circuit) is characterized by its damping being merely dependent on the ohmic resistances contained in it. Now 85 in order to reduce as far as possible the damping of this circuit, which is necessitated by the Joule heat, by the present invention for making the winding a conductor is employed of non-magnetic material of good conductivity, the diameter of which is at least .025 inch. Hitherto a very thin wire was usually employed for this object, about .004 inch diameter—that is to say, about six times thinner than in the present case. Instead of a 95 solid wire a braid or lace may also be em-

ployed in the present case, whereby the losses produced by eddy-currents are also substantially diminished. It is also necessary in order to obtain and maintain as sharp a tuning 5 of the receiver-circuit as possible that the capacity of the same shall remain as far as possible constant. Now, however, the detector which lies in the secondary receiver-circuit represents a capacity which does not 10 remain constant, but, on the contrary, is liable to alterations—for instance, by vibration or from other causes. In order to make these 15 variations to have as slight an influence as possible on the actual periods of the receiver system, by the present invention the total capacity of the receiver-circuit in comparison to the detector capacity is made at least twice as great as the latter. Experiments have 20 shown that such an enlargement of the capacity as compared to the detector capacity makes the fluctuations of the latter almost inoperative on the actual periods of the receiver-circuit. The increase of the capacity of the receiver-circuit may be obtained either 25 by a condenser of suitable size being inserted in parallel to the detector or by the self-induction coils contained in the receiver-circuit being themselves given the necessary capacity by suitable form and construction.

30 The invention will be more particularly described in connection with the accompanying drawings, in which—

Figure 1 is a diagrammatic view of a simple transmitter. Fig. 2 is a diagrammatic view 35 of a single receiver. Fig. 3 is a diagrammatic view of a coupled receiver. Fig. 4 is a diagrammatic view of a coupled transmitter.

Fig. 1 is a simple transmitter which acts in conjunction with the receiver shown in Fig. 2. 40 The latter is formed of an aerial conductor *a*, which is conductively but only loosely coupled with a receiver-circuit *b*. The loose coupling is here attained by only a portion of the total self-induction contained in the receiver-circuit, being employed for coupling with the aerial conductor *a*—that is to say, in other words, only a portion of the coil *c* of the receiver-circuit lying within the aerial conductor *a*. The receiver-circuit contains in addition to this coil *c* a coherer *d*. The self-induction coil is by the present invention formed of a conductor of good conductivity and having a diameter of at least .025 inch. A condenser *f* is switched on in parallel to the coherer, through which condenser the capacity of the receiver-circuit is brought to at 55 least twice the amount of the capacity of the coherer. Instead of loosely conductively coupling the receiver-circuit with the aerial conductor the coupling may also take place inductively, as shown in Fig. 3, the loose coupling being obtained in the ordinary manner—for instance, by leaving a space between the primary and the secondary coils of the converter—or by only a smaller portion of the self-

induction of the receiver-circuit acting in conjunction with the primary coil of the aerial conductor.

Instead of the simple transmitter shown in Fig. 1 there may, as already stated, be employed one having an exciting-circuit—that is to say, a coupled transmitter, as shown in Fig. 4. The exciting-circuit may then be inductively connected with the aerial conductor, as here shown, or even conductively connected 75 while as firm a coupling as possible is desirable.

It is easily evident that the effectiveness of the receiver system hereinbefore described is affected by the size of the spark-gap of the transmitter, inasmuch as the damping of the latter increases with an enlargement of said spark-gap. It has therefore been found preferable for the combined action with the receiver system described in all the cases where 80 the spark-gap exceeds a certain size to employ instead of one large one several small ones—that is to say, to divide the spark-gaps, as shown in Fig. 4. In order in this case to obtain a uniform distribution of the potential 85 charge over the separate spark-gaps, it is necessary to arrange potential-distributors parallel to the separate spark-gaps, which potential-distributors are of less conductivity for the rapid discharge vibrations. As means for 90 distribution of potential very small condensers, self-induction coils, and high ohmic resistance have been found effective. It is easily seen that such a division of the spark-gaps may also be employed with like success 95 in the simple transmitter shown in Fig. 1.

The following have been found to be the most favorable methods of tuning, the number $\frac{\lambda_1 - \lambda_2}{\lambda_0}$ being defined as degree of coupling if 100

λ_0 represent the self-vibration of the exciting-circuit and the aerial conductor separated from one another, and λ_1 and λ_2 the two partial waves of the coupled circuit. In a simple or a firmly-coupled transmitter with receiver-circuit, the coupling degree of which does not exceed a given value, which lies between fifteen per cent. and thirty per cent., the most favorable action is obtained if both circuits of the loosely-coupled receiver be tuned to the self-vibrations of the loosely-coupled transmitter. If a coupled transmitter be coupled firmer than that stated, the tuning is onto a length of wave more clearly approaching the short wave. In still firmer coupling of the coupled transmitter the receiver is preferably tuned to the short wave. For tuning the detector-circuit it is advisable to vary the self-induction of the coil contained in this circuit. In this case the device for varying the self-induction can be provided with an indicator showing on a scale the periods or wave lengths of the detector-circuit which correspond to the actual alterations (or variations) of the self-induction.

Having explained our invention, what we do claim, and desire to secure by Letters Patent, is—

1. In a wireless signaling system the arrangement of a transmitter and a receiver, the receiving-circuit of which is loosely coupled with the aerial conductor and a detector and a self-induction coil within the receiver-circuit, the capacity of the latter being at least twice as large as the capacity of the detector with the object of diminishing the fluctuations of the capacity caused by the detector substantially as described.

2. In a wireless signaling system the arrangement of a transmitter and a receiver, the receiving-circuit of which is loosely coupled with the aerial conductor and a detector and a self-induction coil within the receiver-circuit, the self-induction being formed of a conductor of good conductivity and a diameter of at least .025 inch, in order to diminish as far as possible the damping in the receiver-circuit substantially as described.

3. In a wireless signaling system the arrangement of a transmitter and receiver, the receiver-circuit of which is loosely coupled with the aerial conductor, and a detector and a self-induction coil within the receiver-circuit, the self-induction coil being formed of a conductor of good conductivity and a diameter of at least .025 inch, the capacity of the receiver-circuit being at least twice as great as the capacity of the detector substantially as described.

4. In a wireless signaling system the arrangement of a transmitter in conjunction with a divided spark-gap within the aerial conductor or in an exciting-circuit firmly coupled with the latter, a receiver, the receiving-circuit of which is loosely coupled with the aerial conductor and a detector and a self-induction coil within the receiver-circuit, the capacity of the receiver-circuit being at least twice as great as that of the detector substantially as described.

5. In a wireless signaling system the arrangement of a transmitter conductively or inductively connected with an exciting-circuit, a receiver, the receiving-circuit of which is more loosely coupled with the aerial conductor than the exciting-circuit with the aerial conductor, a detector and a self-induction coil within the receiver-circuit the capacity of which is at least twice as great as that of the detector substantially as described.

6. In a wireless signaling system the arrangement of a transmitter and a receiver, the receiving-circuit of which is loosely coupled with an aerial conductor, and a detector and a self-induction coil within the receiver-circuit, the latter being formed of a conductor of good conductivity and of a diameter of at least .025 inch, and the arrangement of a condenser of sufficient capacity parallel to the detector for diminishing the fluctuations of the capacity caused by the detector substantially as described.

7. In a wireless signaling system the arrangement of a transmitter and a receiver, the receiving-circuit of which is loosely coupled with the aerial conductor, and a detector and a self-induction coil within the receiving-circuit, the latter formed of a conductor of good conductivity and of a diameter of at least .025 inch, and having a capacity which is at least twice as great as that of the detector substantially as described.

8. In a wireless signaling system the arrangement of a transmitter in combination with a divided spark-gap, means of lesser conductivity for the rapid discharge vibrations parallel to the separate spark-gaps, a receiver, the receiving-circuit of which is loosely coupled with the aerial conductor, a detector and a self-induction coil within the receiver-circuit, the capacity of the latter being at least twice as great as that of the detector, and the self-induction coil being formed of a conductor of at least .025 inch diameter substantially as described.

9. In a wireless signaling system the arrangement of a transmitter and a receiver, the receiving-circuit of which is loosely coupled with the aerial conductor, a detector and a self-induction coil within the receiver-circuit, the self-induction coil being formed of a conductor of at least .025 inch diameter, means for altering the self-induction of the coil and means for inducting the wave lengths or periods of the vibrations of the receiver-circuit which correspond to the actual alterations (or variations) of the self-induction substantially as described.

In witness whereof we hereunto subscribe our names this 23d day of August, A. D. 1904.
